UNITED STATES PATENT OFFICE.

HORACE L. McCURDY, OF OAKWOOD, MICHIGAN, ASSIGNOR TO EDWARD MOXLOW, OF OAKWOOD, MICHIGAN.

CARBURETER.

1,324,510.

Specification of Letters Patent.

Patented Dec. 9, 1919.

Application filed January 7, 1918. Serial No. 210,613.

To all whom it may concern:

Be it known that I, HORACE L. McCURDY, a citizen of the United States, and residing at Oakwood, in the county of Wayne and State of Michigan, have invented a new and Improved Carbureter, of which the following is a specification.

This invention relates to devices for carbureting liquid fuel for internal combustion engines, and its object is to provide a valve to control the flow of fuel into the carbureting chamber which valve shall be opened in proportion to the movement of an actuating member, and to provide a valve operatively connected to the fuel valve to control the flow of air through the carbureting chamber whereby the reduction of air pressure in the carbureting chamber may be varied to cause the production of mixtures of the proper richnesses for the different conditions of operations of the engines.

This invention consists in the details of construction illustrated in the accompanying drawings and more particularly pointed out in the claims.

In the accompanying drawings, Figure 1 is a side elevation of this improved carbureter. Fig. 2 is a plan thereof. Fig. 3 is a central vertical section at right angles to Fig. 1. Figs. 4 and 5 are sections on the line 4—4 of Fig. 3, showing the air valve in two different positions. Fig. 6 is a view of the fuel valve and its operating stem. Fig. 7 is a view of the air valve. Figs. 8, 9 and 10 are views of the same valve from different sides. Fig. 11 is a detail sectional view on a larger scale of the upper end of fuel passage.

Similar reference characters refer to like parts throughout the several views.

The carbureter shown in the drawings has a float chamber 1 having a top 2 that constitutes the bottom of the valve or carbureting chamber. A threaded sleeve 3 connects to any source of fuel supply, and the small fuel passage 4 may be closed by the float valve 5 that rests on a plate 6 carried by the float 7 which is pivoted on the pin 9 carried by two arms 10. This construction forms no part of my invention.

A tube 12 screws up into the top 2 of

the float chamber and has a central passage 13 that ends at its lower end at the cross passage 14 which is covered by a screen 15. A second cross passage 16 connects to the short longitudinal passage 17 that is normally closed by means of the screw plug 18. By turning back this plug, the float chamber may be drained through the passages 16, 17 and 19. A nut 20 on the lower end of the tube 12 holds the float chamber and drain plug 18 in position.

Above the top 2 of the float chamber is a valve chamber 22 which is preferably cylindrical and which has a cover 23. In this chamber is rotatable the air valve 24 having a tubular stem 25 on which is mounted an operating arm 26. This arm is secured to the stem by means of a screw 27 and the arm carries a stop-screw 28 which limits the movement of the valve through engagement with the abutment 29. The motion in the opposite direction is limited by the projection 30 on the arm 26. Any other operating device for the valves may be employed.

Extending down through the valve stem 25 is a stem 32 which is held from turning in the stem 25 in any desired manner. As shown in Fig. 2, the stem 25 is formed with radial slots 33 and the fingers formed thereby may be caused to grip the stem 32 by means of a nut 34. The stem 32 has a tongue 38 at its lower end that extends into a slot in the upper end of the valve 35. Pins 36 extend through this stem 32 and position it relative to the stem 25.

The valve 35 is shown in Figs. 3 and 6 to consist of the hollow lower threaded portion 37 having transverse passages 40 just below the shoulder 39. The upper end of the tube 12 is locked to the top 2 by means of a nut 42, and the upper end of the passage 13 is counterbored to form a cup shaped depression 41, the upper end of which is slightly larger than the shoulder 39. In a carbureter adapted to the Ford cars the effective distance between this shoulder and the wall of the depression varies from .0015 inch when the engine is idling to .004 inch when the engine is working at full power. The diameter of the shoulder is .185 inch and the

diameter of the threaded portion 37 is .1285 inch. The wall of the cup at the upper end of the tube 12 are preferably at an angle of 60 degrees to the horizontal. These 5 dimensions are not necessarily the best for all engines but good results have been obtained with many hundred carbureters embodying them.

A butterfly-valve 44 on the stem 45 is 10 shown mounted on the intake passage 46. The valve 24 has a circular outlet opening which registers with the outlet passage 48 when the valve is entirely open, as shown in Figs. 3 and 4, but which is nearly closed 15 when the engine is idling, as shown in Fig. 8. As shown in Fig. 9, the oval inlet opening 49 in this valve is slightly smaller than the outlet opening, which will cause a slight decrease in pressure or increase in suction 20 within the valve and a slight proportional increase in the flow of fuel when the air valve is entirely open.

When the engine is idling, the proportional flow of fuel is reduced by forming a 25 hole 50 in the wall of the valve, as shown in Fig. 10, which will register with the intake passage 46, and thereby reduce the suction within the valve and thereby reduce the proportional flow of fuel. When the air 30 valve is opened for low working speeds, the two auxiliary passages 51 are uncovered and register with the inlet passage 46, thus again reducing the richness of the mixture. Not until the engine is working at more than 35 half its full capacity does the air inlet increase more slowly in size than the outlet 47.

It will be remembered that the effective 40 distance that the fuel valve is opened depends entirely on the distance it is turned, but the flow of fuel will also depend upon the suction, and this will be greatest when the valve is in the position shown in Fig. 4. The suction will be least when the engine is 45 idling, so that the leanest mixture will then pass to the engine. The mixture will slowly become richer after the passages 51 have registered with the inlet passage 46.

The details and proportions of the various 50 parts of this carbureter may be changed by those skilled in the art without departing from the spirit of my invention set forth in the following claims.

I claim:—

1. In a carbureter, the combination of a 55 float chamber having a central vertical screw threaded discharge passage, a hollow rotatable fuel valve screwed into the passage and having a circumferential shoulder just above the upper end of the passage and radial 60 holes through its wall just below the shoulder, a cylindrical carbureting chamber above the float chamber and concentric with the fuel valve, an air valve rotatable therein and provided with radial inlet and outlet

openings, a central stem extending down 65 into said air valve in alinement with the fuel valve, said stem and valve having a slideable operable connection, and means to turn the valves.

2. In a carbureter, the combination of a 70 float chamber having a central vertical screw threaded discharge passage, a rotatable fuel valve screwed into said passage and provided with discharge openings, a cylindrical mixing chamber and a cylindrical air 75 valve mounted above the float chamber concentric with the fuel valve and extending below said discharge openings in the fuel valve, said air valve and carbureting chamber having radial inlet and outlet passages, 80 and means connecting the air and fuel valves to cause them to turn together but permit longitudinal movement between them.

3. In a carbureter, the combination of a carbureting and float chambers, a stem extending from the bottom of the float chamber to the carbureting chamber, and having a transverse passage at its lower end, and a longitudinal passage extending therefrom to the carbureting chamber, a screen over 90 the transverse passage, a second transverse passage below the first and independent thereof, a longitudinal passage extending downwardly therefrom, and a valve to close the lower end of said second longitudinal 95 passage said carbureting chamber having inlet and outlet openings.

4. In a carbureter, the combination of a cylindrical carbureting chamber having an air inlet and an outlet for the explosive mixture, an air valve rotatable therein and formed with a circular outlet and with an oval main inlet and smaller auxiliary inlets, a fuel passage connecting into the bottom of said chamber, a fuel valve co-axial with 105 the air valve rotatable in said passage, and means connecting said valves so as to cause them to turn together.

5. In a carbureter, the combination of a cylindrical carbureting chamber and an air 110 valve rotatable therein, a tubular fuel passage connecting into the bottom of said chamber co-axially with the air valve and having its upper end cupped and internally threaded, a fuel valve having a tubular 115 lower end screwed into said passage and a shoulder just above radial holes connecting into the space in the lower end of the valve, said shoulder being adapted to move in and out of the cupped end of the passage as the valve is turned to regulate the flow of fuel into the carbureting chamber, and means connecting said valves so as to cause them to turn together.

6. In a carbureter, the combination of a 120 float chamber having a top and a central vertical screw threaded discharge passage in said top, a hollow rotatable screw-threaded

fuel valve mounted in said passage and having a transverse notch in its upper end and radial holes at the upper face of the top of the float chamber, a hollow air valve having 5 an open lower end rotatably mounted on the top of the float chamber concentric with the fuel valve, and having inlet and outlet

openings, a valve chamber containing the air valve and having inlet and outlet openings, a central stem adjustably mounted in 10 the air valve having a flattened lower end extending into the notch in the fuel valve, and means to turn said air valve.

HORACE L. McCURDY.
